MERCURY DISPENSER

Harold E. Baker, Danvers, Mass., assignor to Sylvania Electric Products Inc., Salem, Mass., a corporation of Massachusetts

Application March 7, 1951, Serial No. 214,380

1. Claim. (Cl. 226—19).

1.

This invention relates to the manufacture of electric gaseous discharge devices and more particularly to apparatus for introducing mercury into said devices during the manufacture thereof.

In the art of manufacturing certain electric gaseous discharge devices, such as fluorescent lamps for example, a small amount of mercury is introduced into the devices during the manufacture thereof. In many cases, the quantity of mercury to be introduced is a definite, predetermined amount and any substantial deviation therefrom adversely affects the device.

An object of this invention is to provide electric gaseous discharge devices with a filling of a definite, predetermined quantity of mercury.

Another object is to provide an apparatus which will dispense a definite, predetermined amount of mercury.

A further object is to provide a mercury dispenser which is positive in its action and dispenses a uniform predetermined amount of mercury each time it is actuated.

The foregoing objects and others are attained, in accordance with the principles of this invention, by providing a reservoir with a plunger disposed therein which, when actuated, shears a predetermined amount of mercury from a supply thereof in the reservoir and drops it directly into the device which is to be provided with a filling of mercury.

A specific embodiment of this invention is described in the following specification and illustrated in the accompanying drawings in which:

Figure 1 is a fragmentary plan view of a fluorescent lamp exhaust machine showing the location of an embodiment of the invention thereon.

Figure 2 is a fragmentary side elevational view of the machine of Figure 1.

Figure 3 is an enlarged side elevational view in section, taken along line 3—3, of a station on the machine of Figure 1, showing the mercury dispenser of this invention. In this figure, the plunger of the mercury dispenser is shown in its normal rest position.

Figure 4 is a plan view in section of the mercury dispenser taken along the line 4—4 of Figure 3.

In Figure 1, that portion of a fluorescent lamp exhaust machine shown therein comprises a rotatable turret 1 supported on a vertical column 2. The turret 1 comprises a hub 3, a plurality of supporting arms 4 extending radially therefrom, and a ring plate 5 mounted on the outer ends of the arms 4. In Figure 2, a plurality of lamp exhaust heads 6 are mounted on the top face of

the ring plate 5. Fluorescent lamps 7 having exhaust tubes 8 projecting from an end thereof are disposed beneath the heads 6 and in register therewith, the exhaust tubes 8 extending through apertures provided therefor in the ring plate 5 and into the exhaust heads 6. The exhaust heads 6 are connected to a vacuum system which is not shown since the illustration thereof is not necessary for a complete understanding of this invention. The fluorescent lamps 7 are held in position by fingers 9 on rods 10 depending from the ring plate 5.

Each exhaust head 6 has a mercury dispenser 11 mounted on the top thereof. Actuation of the mercury dispensers 11 is effected by electromagnets 12, two of which are shown in Figures 1 and 2. The electromagnets 12 are connected to a source of electrical energy (not shown) by means of wires 13 extending therefrom. A spider 14 is fixedly mounted on the column 2 and is disposed above the turret 1. An arm 15 is mounted on the spider 14 and extends radially therefrom. The electromagnets 12 are mounted on a plate 16 attached to the outer end of the arm 15.

In Figure 3, the mercury dispenser 11, which is mounted on the exhaust head 6, has two main components, a jacket 17 and a plunger 18 disposed therein. The jacket 17 has a reservoir 19 therein for a supply of mercury 20. The jacket 17 has a base 21 which is screwed into the top of the exhaust head 6. The exhaust head 6 is bored to provide a funnel 22 therein immediately below and in register with the mounting position of the jacket 17. This funnel 22 is in communication with the exhaust tube 8 of the lamp 7. The base 21 of the jacket 17 is bored through from the end thereof to the floor 23 of the reservoir 19. The hole formed thereby is made larger in diameter at the end of the base 21 and this opening is identified by reference numeral 24, whereas the smaller opening in communication with the reservoir 19 is identified by reference numeral 25.

The plunger 18, which is disposed in the jacket 17, has a head 26 normally located above the surface of the mercury supply 20 and a shank 27. The shank 27 extends downwardly through the openings 24 and 25 in the base 21 of the jacket 17. The lower portion 29 of the shank 27, which is disposed in the openings 24 and 25 in the base 21, is smaller in diameter than the upper portion 27, the point of demarcation between the two diameters defining a shoulder 28 which seats on the floor 23 of the reservoir 19 when the plunger is in the rest position. The

lower portion 29 of the shank 27 has a recess preferably a notch 31, cut in its periphery. The plunger 18 is preferably tubular having a hole 32 bored completely through it along its longitudinal axis, and the head 21 thereof preferably has cut-outs 33 (Fig. 4) in its periphery to prevent any pressure being built up in the mercury reservoir due to the operation of the plunger 18.

The top of the jacket 17 is provided with a shelf 34 on which a ring 35 of resilient material, preferably circular in cross-section, is located. A pressure plate 36 is positioned on top of the ring 35. The top of the jacket 17 is closed by a threaded cap 37 which, when turned down hand-tight, engages the top of the pressure plate 36 and thereby effectively seals off the mercury supply 20 from the atmosphere.

The jacket 17, the pressure plate 36 and the cap 37 are all made of a non-magnetic metal which is not attacked by contact with mercury, such as non-magnetic stainless steel, whereas the plunger 18 is made of magnetic metal which is not attacked by contact with mercury, such as magnetic stainless steel.

The operation of the mercury dispenser of this invention will now be described. As mentioned above, a mercury dispenser 11 is mounted on each head 6 of a rotatable turret type lamp exhaust machine which carries the heads 6 to a plurality of work stations at which various operations are performed on the lamps 7 which are connected to the heads. One of these operations is the introduction of mercury into the lamps, which is performed at the mercury-filling station. The particular machine with reference to which the mercury dispenser of this invention is illustrated is provided with two mercury-filling stations in order to permit two lamps to have mercury introduced therein at the same time. When this is accomplished the machine indexes and two more lamps are brought into position to have mercury dispensed thereto.

Referring now to Figures 1 and 2, when a pair of heads 6 reach the mercury-filling position beneath the electromagnets 12, the electromagnets are energized. Referring now to Figure 3, energization of the electromagnet 12 draws the plunger 18 upwardly until the notch 31 in the periphery of the lower portion 29 of the shank 27 thereof is disposed above the floor 23 of the reservoir 19. When the plunger 18 is so located, some of the mercury 20 will flow into and fill the notch 31. The electromagnet 12 is then de-energized, thus permitting the plunger 18 to drop back to its starting position with the shoulder 28 on the shank 27 of the plunger seating on the floor 23 of the reservoir 19. As the plunger drops and the notch 31 moves down into the opening 25 in the base 21 of the jacket 17, the mercury which had previously entered the notch is sheared from the main supply 20 thereof by the wall of

the opening 25. This drop of mercury, the quantity of which is accurately predetermined by the size of the notch, is retained in the notch 31 until the plunger drops down far enough for the notch 31 to be located in the opening 24. Since the opening 24 in the base 21 of the jacket 17 is substantially larger in diameter than the diameter of the lower portion 29 of the shank 27 of the plunger 18, the drop of mercury in the notch 31 will fall out and drop through the funnel 22 in the head 6 and into the lamp 7 through the lamp exhaust tube 8. Any tendency which this drop of mercury may have to stick in the notch 31 after the notch enters the opening 24 in the base 21 of the jacket 17 is obviated by the shock of the shoulder 28 on the shank 27 of the plunger 18 seating on the floor 23 of the reservoir 19.

What I claim is:

Apparatus for dispensing measured amounts of mercury comprising: a rotatable turret moveable to a plurality of work stations; a reservoir fixedly mounted on said turret, said reservoir being of non-magnetic metal, having a body of mercury therein and an opening in the bottom thereof; a plunger of magnetic metal having a head and a shank disposed completely within said reservoir, said head being disposed immediately above the surface of the body of mercury, and said shank extending through the opening in the bottom of said reservoir and in sliding contact with the wall of the upper portion of said opening, said plunger having a recess cut in the periphery of its shank and normally disposed below that portion of the opening in the bottom of the reservoir with which the shank is in sliding contact; a cap of non-magnetic metal closing the top of said reservoir, and an electromagnet fixedly mounted above and in register with one of said work stations and disposed above, in close proximity, and, at all times, maintaining the same vertical spacing between itself and the cap of the reservoir for permitting unobstructed movement of said reservoir to a position beneath the electromagnet and in which position the electromagnet, without moving, is effective to reciprocate said plunger to carry the recess in the shank thereof into contact with the body of mercury in said reservoir and return with a drop of mercury therein.

HAROLD E. BAKER.
